UNITED STATES PATENT OFFICE.

CARL H. KRONEWITTER, OF INDIANAPOLIS, INDIANA.

VEHICLE-SPRING LUBRICATOR.

1,418,580.

Specification of Letters Patent. Patented June 6, 1922.

Application filed May 24, 1920. Serial No. 383,936.

To all whom it may concern:

Be it known that I, CARL H. KRONEWITTER, a citizen of the United States, residing at Indianapolis, in the county of 5 Marion and State of Indiana, have invented a new and useful Vehicle-Spring Lubricator, of which the following is a specification, reference being had to the accompanying drawings and to the letters and figures 10 of reference marked thereon.

This invention relates to an appliance whereby leaf-springs of vehicles, especially motor vehicles, may be constantly supplied with lubricating oil, the invention having 15 reference more particularly to a type of lubricator that is designed to hold oil conveniently to the leaves of vehicle springs so that the oil may flow between the leaves of the springs.

An object of the invention is to provide a 20 lubricator appliance which shall be so constructed as to be adapted to be readily applied in various ways to lubricate leaf springs, to insure free and noiseless working of the springs, and to prevent rapid wear of the leaves of the springs. Another object is to provide a simple and efficient lubricator appliance which shall be of such construction as to be adapted to be applied by 25 the unskilled to springs already in use which may not have been previously provided with lubricating appliances, so that in case of accidental damage a lubricator may be easily discarded and a new one put in its 30 place. A further object is to provide an improved spring-lubricator of the above-mentioned character that shall be plain and easily cleaned, and not require a separate obstructive oil-cup, and which may be produced at small cost and be durable and economical in use.

With the above mentioned and other objects in view, the invention consists in a vehicle spring-lubricator having certain novel 45 features of construction, and in the parts and combinations and arrangements of parts as hereinafter particularly described and further defined in the accompanying claims.

Referring to the drawings, Figure 1 is a 50 fragmentary view showing portions of an automobile by broken lines and a leaf-spring thereof provided with the improved lubricators as they may conveniently be arranged on the springs. Fig. 2 is a transverse section of a leaf-spring and the improved lubricator applied thereto, portions of a

lubricator being shown by broken lines in unfolded position, as when the lubricator is being applied or removed. Fig. 3 is a perspective view of the casing of the improved 60 lubricator in which portions thereof are unfolded to permit it to be applied to a spring. Fig. 4 is a sectional elevation showing a portion of the leaf-spring having the improved lubricator applied thereto and ready to be 65 secured in place. Fig. 5 is a transverse section of a leaf-spring having the lubricator applied thereto, the fastening devices of the lubricator being of slightly modified form; and, Fig. 6 is a perspective view of an absorbent lubricant-holding part of the 70 improved lubricator.

Similar reference characters in the different figures of the drawings indicate corresponding elements or features of construction herein referred to in detail.

In the drawings the numeral 1 indicates an automobile or vehicle frame, 2 an axle supporting a spring having leaves 3, 3' and 3'', the spring supporting the frame, and 4 80 and 4', generally indicate the improved lubricators as they may be arranged on the spring.

In practically carrying out the objects of the invention a metallic casing is provided 85 which preferably is composed of sheet metal and comprises a flat top plate 5 from which extends ends having main portions 6 and 7 respectively from which extend angular portions 8 and 9 having tapered clasp portions 90 10 and 11 respectively to engage the underside of a spring. The clasp portions may be variously adapted to be secured together under the spring, but preferably one clasp portion has a transverse slot 12 therein and 95 the opposite clasp portion has a projecting tongue 13 adapted to be inserted through the slot and bent over to form a hook. The top plate has sides 14 and 15 on opposite edges 100 thereof to rest upon the top of the spring and retain the absorbent part. Preferably the main portions 6 and 7 of the ends have side members 16 and 17 respectively on one edge thereof and similar members 18 and 19 on the opposite edge thereof to assist in 105 holding the absorbent part and to retain the lubricant.

In some cases the clasp portions may be slightly modified and have ears 20 and 21 thereon respectively that are provided with 110 a securing bolt 22 to fasten the casing to a spring. The casing is made of suitable thin

metal so that the ends that have the clasp portions may be first made straight and afterwards bent under the spring and connected together. Preferably the side members 16 and 17 have relatively oblique lower edges 23 and 24 and the opposite members 18 and 19 have similar lower edges 25 and 26, to correspond to the inclined portions, as 8 and 9.

10 A suitable absorbent part or filling 27 is provided which is flat and has a central aperture 28 to constitute an oil reservoir, and the part is designed to rest directly upon the top of the spring within the casing 15 and has downward extending members 29 and 30 having lower bevel ends 31 and 32 respectively to correspond approximately to the angularity of the end portions 8 and 9. The absorbent part is composed of suitable 20 felt or spongy material adapted to retain oil to ooze therefrom.

To permit the oil reservoir to be refilled, the top plate 5 of the casing has two parallel slits 33 and 34 connected by a cross slit 35 25 so as to produce an elastic tongue-like cover for the oil reservoir integral with the top plate and which may be slightly flexed inward by the spout 37 of an oil can.

In practical use, a lubricator having been 30 fastened on a spring so that the absorbent part or filling shall embrace the top and sides of the spring, the oil reservoir is supplied with lubricating oil which is absorbed by the adjacent fibrous substance, the oil 35 gradually working downward and between the leaves of the spring, and through capillary attraction the oil will gradually work upwards between the leaves, the oil obviously flowing downwards also on inclined portions 40 of the leaves. When additional oil is required the cover 36 may be slightly pressed downward and oil inserted through the aperture in the top plate to the oil reservoir. The top plate, being a plane is not a dirt- 45 catcher and may be readily cleaned.

Having thus described the invention, what is claimed as new is,—

1. In a leaf-spring lubricator appliance,

an absorbent part comprising a top portion and two side portions, each side portion having a beveled end, the angle of the end being obtuse to the outer face of the side portion, in combination with a casing to embrace said part and said beveled ends thereof.

2. In a leaf-spring lubricator appliance, the combination of an absorbent comprising two side portions having each a beveled end with a top portion connected to the side portions, a casing comprising a top plate and two end members embracing the absorbent, the end members having inclined bottom portions respectively embracing said beveled ends respectively, and two clasp portions extending from said inclined bottom 65 portions respectively, there being sides on said top plate and also sides on each of said end members, the sides on the end members having beveled ends corresponding to and co-operating with the edge portions of said 70 inclined bottom portions respectively.

3. In a leaf-spring lubricator, the combination of a casing comprising a flat top plate having an opening therein, a closure integral with the plate at one side of and 75 extending into said opening, the closure and the plate being on one and the same plane, two end members integral with said top plate and comprising each a main portion and a tapered flexible clasp portion, each 80 clasp portion being adapted to be connected to the other clasp portion, two side members on said top plate, two side members having each a beveled end on one of said main portions, and two side members having each a 85 beveled end on the remaining one of said main portions, with an absorbent part in the casing comprising side portions having beveled ends corresponding to the beveled ends of said side members.

In testimony whereof, I affix my signature in presence of two witnesses.

CARL H. KRONEWITTER.
